SYSTEM OF OPERATING DEVICES IN TIMED
RELATION

Clyde J. Fitch, Endicott, N. Y., assignor to International Business Machines Corporation, New York, N. Y., a corporation of New York

Application October 20, 1936, Serial No. 106,546

13 Claims. (Cl. 178—69.5)

This invention relates to synchronizing systems and more particularly to electronic synchronizing systems.

An object of the present invention is to provide 5 a novel and more efficient synchronizing system which comprises wholly electrical means such as electronic discharge devices to maintain synchronization between remotely situated stations.

Other objects and features reside in the provision of means to generate the source of power 10 at the remote stations and simultaneously to transmit control signals initiated by the generated power to control the generation of the supply power at a different remote station.

15 It will be obvious from the description herein that the present invention will have innumerable applications, in fact, it is applicable to practically all systems wherein apparatus, such as rotary equipment used in various forms of communication systems such as television, facsimile, printing telegraph systems, etc., or electronic apparatus operating on a timed basis or utilizing a timed power supply which must be in exact phase relationship.

20 Various other objects and advantages of the invention will be obvious from the following particular description of one form of mechanism embodying the invention or from an inspection of the accompanying drawing; and the invention 25 also constitutes certain new and useful features of construction and combination of parts herein-after set forth and claimed.

In the drawing:

Fig. 1 shows diagrammatically the circuit connections of a preferred form of the present synchronizing system.

Figs. 2 to 6 represent various characteristic curves of the wave forms of the system.

Referring now to Fig. 1, a brief general description of the system will be given before describing in detail the preferred form of circuit connections. The electron discharge devices 1 and 2 and associated circuits comprise a constant frequency oscillator system, so that upon closure of the control switch 3, the triode arrangement of tube 1 is activated to operate the normally high biased tube 2 permitting the tuned circuit 4 in the plate circuit thereof to be excited momentarily. The oscillations generated by the tuned circuit are in turn impressed upon amplifier 5 and filter 6 and the duplex diode arrangement of tube 1. The rectified waves are then impressed upon the triode of tube 1 so that a short control signal is impressed upon the electron discharge devices 2 and 7. The control sig-

nal activates the tube 2 to permit the tuned circuit to be excited as just explained to energize tube 1, thus establishing an oscillatory circuit arrangement capable of generating oscillations at a substantially constant frequency. 5

The oscillation generator described is the subject matter of a copending application Serial No. 100,070, filed Sept. 10, 1935, and may be referred to for a more complete description.

At the terminals 8—8, which are a source for 10 constant frequency AC, any suitable equipment to be controlled may be connected and is generally designated at 14. This apparatus, as it will be understood as the description progresses, may be of various types, such as rotary apparatus, 15 electronic devices or other elements which are to be controlled in a certain timed relationship with other similar apparatus remotely located. Upon closure of the switch 9 the control signals activating tube 7 at a certain definite frequency 20 are then impressed upon the circuit 10 which may be any form of transmission media desired. The said signals activate the electron discharge devices 11, 12 and 13 designated to be located at a remote station B so as to generate a constant 25 frequency AC in the same manner as at the original station A to operate similar apparatus thereat and designated at 14—a. The exact mode of operation thereof will now be set forth.

The electron discharge device 1 is shown comprising the combination of a full wave rectifier and triode in one envelope and is a type well known in the art and commonly referred to as a duplex diode triode type. The diode plates 15 and 16 are joined to the terminals of resistor 17, 30 the center tap of which is connected to the grid 18 of the tube. A resistance 19 is inserted between the said center tap and the cathode of the tube. A condenser 20 is connected across the cathode and diode plate 16, the purpose of which 35 will be understood as the description progresses. The triode plate 21 is connected to positive battery by means of the control switch 3 and the negative side thereof is extended to the cathode of the tube through resistor 22 and inductive winding or coil 40 23. It is understood that normally the grid 18 of the tube is at zero bias due to the fact that no current is passing through resistor 19, and therefore that upon closure of the control switch 3 current will flow through the tube 1 from the 45 triode plate to cathode and through the resistance 22 and coil 23 to the negative side of the battery. The primary winding of transformer 24 is connected in shunt with the resistor 22 and the secondary winding thereof is included in addition 50

to the resistance 25 in the grid circuit of tube 2. A negative potential is shown normally applied to the said grid so that the tube is normally biased below cut-off. Associated with the plate of tube 2 is an oscillatory circuit 4 which is energized upon operation of the control switch 3 due to the said current flow in the triode plate circuit of tube 1. The initial voltage drop across resistor 22 is impressed upon the grid of tube 2 by means of transformer 24 and is sufficient to overcome the bias of the grid so as to cause a signal pulse to flow from positive side of source 26 through the tuned circuit 4, the plate and cathode of tube 2 to the negative side of said source. The excitation of the tuned circuit at a frequency depending upon the LC constants of the circuit is impressed upon the coupling condenser 27 and the input to amplifier 5. Between the tuned circuit and the input of the amplifier, phase shifting means is provided comprising the combination of condenser 27 and variable resistance 28. The phase shift may be effected and varied slightly by means of adjusting the resistor 28 for final adjustment, the purpose and application of which will be described later herein.

The generated oscillations are amplified and passed through the filter 6 which is used merely for the purpose of filtering out the higher harmonics and for delivering a pure sine wave at the output of the filter which in turn is impressed upon the terminals of resistor 17. It was mentioned hereinbefore that normally the grid 18 of tube 1 is at zero bias since there is no current passing through resistor 19. However, upon impression of the amplified oscillations at the terminals of the said arrangement the rectified waves passing through resistor 19 immediately drive the grid bias negative to prevent current flow in the triode plate circuit. Before the grid bias is effective to reduce the flow of plate current a short pulse is impressed upon the triode output circuit of tube 1 which includes the resistor 22 and coil 23. It was also mentioned that a condenser 20 is inserted between the cathode and one of the diode plates of the rectifier of tube 1. The curve in Fig. 3 shows the sinusoidal wave impressed across the diode plates of the tube. When the polarity is such that current passes from one diode plate 15 to cathode, this current passes through resistor 19 charging the condenser 20 to the polarity as shown. At the end of this particular half cycle as the current passes through zero, the charge in the condenser maintains the grid of the tube negative with respect to the cathode of a value sufficient to permit no plate current to flow. The charge in the condenser leaks off through the resistor 19, and the values of the capacitance and resistance being such that the time constant of the circuit is adjusted to maintain the tube biased below cut-off during the timed interval that the said half cycle of the A. C. wave passes through zero. The following half cycle passing from diode plate 16 to cathode and resistor 19 has reached sufficient amplitude to maintain the tube biased below cut-off. At the end of the second half cycle the charge in condenser 20 has completely leaked off, and so as the second half cycle passes through zero, the grid bias is zero and plate current again is permitted to flow through the tube impressing an impulse upon the output circuit of the triode including resistor 22 and coil 23. The curve in Fig. 4 shows the wave shape of the rectified volt-

age across the resistor 19. The effect of condenser 20 is evident, suppressing the alternate peaks of the rectified wave as shown and as just explained the suppressed waves are reduced in amplitude so as to be ineffective to send out signals in the plate circuit whereas the unsuppressed waves are effective to impress signals upon the output circuit and thus it is seen that but a single impulse is transmitted for a complete cycle of the input oscillations. The impulses impressed upon resistor 22 then activate the input and output circuits of tube 2 as explained to continue initiating the oscillations by virtue of the tuned circuit 4. This action is repeated and the explained circuits continue to oscillate, impulses being impressed upon the grid of tube 2 and the generated A. C. impressed upon the terminals of resistor 17 and an inverted rectified wave impressed upon the grid of tube 1. The curve in Fig. 2 shows the wave shape across the said oscillatory circuit and Figs. 3 to 5 show the other wave shapes in other sections of the circuit as explained, Fig. 5 indicating the short pulses in the output circuit of tube 1 and impressed upon resistor 22 and coil 23.

The phase relationship of the waves generated by the oscillatory circuit, the waves impressed upon the diode plates of tube 1, and the impulses applied to the grid of tube 2 should be such that the impulses in the output circuit of tube 1 are impressed upon the grid of tube 2 during the peak or maximum amplitude of the sine wave generated in the tuned circuit. This relationship is clearly shown in the curves shown in Figs. 2 to 5 and can be effected by inserting, for example, condenser 29 in one side of the filter output circuit as shown. Since the impulses flowing through the plate circuit of tube 1 occur at the zero point of the waves impressed thereupon, and since they must be impressed upon the grid of the tube 2 at the peak of the generated wave in the tuned circuit, it is obvious that the phase relationship between the terminals of resistor 17 and the tuned circuit must be 90 degrees apart. This phase shift may be varied slightly by means of the adjustable resistor 28 for a final adjustment.

From the terminals 8-8 connected to the output of the filter, a pure sine wave generated by the tuned circuit may be amplified and impressed upon any circuit connected thereto and adaptable for use with an oscillation or A. C. generator. The circuit may supply energy to familiar forms of rotary apparatus, or to electronic apparatus or other elements designed to be operated by the generated source and adapted to be operated in a timed relationship to similar apparatus or elements located remotely therefrom. The apparatus or elements are designated generally at 14 and 14a located at stations A and B, respectively.

The description thus far has been limited to the generation of the controlling energy at the station A and the method for maintaining a source of a constant frequency supply.

The impulses shown in Fig. 5 which are impressed upon the output circuit of tube 1 not only energize the resistor 22 for purposes of generating the A. C. energy at the station A as explained but also energize the coil 23 included in the grid circuit of tube 1. The said coil or winding may be considered as comprising inductance and capacitance, the distributed capacity of the winding, which is indicated in

dotted lines at 30, being sufficient for the present operation. The said winding shunted by the distributed capacity as shown may be considered as a tuned circuit generating sine waves when 5 impulses are impressed upon it and is tuned to a multiple of the frequency of the generated oscillations. However, the said circuit is highly damped by the resistor 31 so that just one complete oscillation per impulse impressed thereupon 10 is applied to the grid of tube 7, which in the present example is biased as indicated for operation near the center of its characteristic curve so that the wave is applied without distortion and impressed upon the output transformer 32. 15 Referring to Fig. 6, the curve shows the wave shape developed by the circuit just described, the said waves, virtually a pure sine wave, are in exact phase relationship with the waves shown in Fig. 3 which are impressed upon the diode plates of tube 1.

Upon closure of switch 9 the signals impressed upon the output transformer and shown in Fig. 6 are impressed upon the transmitting medium represented at 10, the receiving transformer 33 at station B and the grid of tube 11, which is normally biased below cut-off so that no plate current can pass through the tube until a signal pulse is impressed thereupon to drive the tube to zero bias, but no farther due to the series grid resistor 34. The output circuit of tube 11 is energized and comprises the following circuit: from positive battery of source 35, plate to cathode of tube 11, plate to cathode of tube 12, resistor 36 to the negative side of source 35. The tube 12 is a duplex diode triode type similar to the tube 1 at station A and as seen the diode plate connections and the grid circuit are the same as described in conjunction with tube 1, so that it is evident that during the intervals that 20 no signal is impressed upon the diode plates and resistor 19—a the tube is at zero bias thereby permitting the circuit described through the tube to be completed. Energization of resistor 36 included in the output circuit of tube 12 activates 25 the grid circuit of tube 13 to energize the tuned circuit in the output circuit thereof to generate oscillations of a frequency equivalent to the frequency generated at station A. The generated oscillations are applied to an amplifier and filter 30 as indicated and then to the diode plates of tube 12 exactly as explained hereinbefore. The operation of tubes 12 and 13 is similar to the operation of tubes 1 and 2, with the exception as just mentioned, namely, that the output circuit of tube 12 35 is controlled by the signal pulses energizing the tube 11.

At the terminals 37—37, a circuit may be connected thereto, and upon which is impressed the generated AC energy which is then amplified and 40 connected to the apparatus or elements designated 14—a which are operated in timed relationship with similar apparatus at station A and indicated at 14.

While there has been shown and described and 45 pointed out the fundamental novel features of the invention as applied to a single modification, it will be understood that various omissions and substitutions and changes in the form and details of the device illustrated and in its operation may 50 be made by those skilled in the art without departing from the spirit of the invention. It is the intention therefore to be limited only as indicated by the scope of the following claims.

What is claimed is as follows:

75 1. In a system for operating devices in timed

relation comprising, in combination, means to generate oscillations at one station including means to initiate periodically timed control signals, a device controlled by the oscillations at the said station, means to transmit the controlled 5 signals, a second oscillation generating means, means controlled by the controlled signals to control intermittently and periodically the operation of the second mentioned oscillation generating means, and a device controlled by the oscillation 10 generated at the last mentioned station so that the two mentioned devices are operated in timed relationship.

2. The method of operating devices in timed 15 relation which comprises generating oscillations of a predetermined frequency for a device at one station and initiating periodic control signals bearing a definite frequency relation with that of the generated oscillations and utilizing the signals to control intermittently and periodically the 20 generation of oscillations at a second station for a device thereat, thereby operating the said devices in timed relationship.

3. A system for operating devices in timed 25 relationship comprising, in combination, means to initiate periodically timed control signals at one station, means controlled by said signals to generate a constantly varying supply energy, a device controlled by the supply energy and means to transmit the control signals, means at a second 30 station controlled by the transmitted signals to generate a supply energy varying in timed relation with the first mentioned supply energy, and a device situated thereat and controlled by the supply energy generated so that the said devices 35 are operated in a predetermined timed relationship.

4. A system of the character described comprising, in combination, means to initiate periodically control signals, a circuit including oscillation generating means energized by the said control signals to produce oscillations of a predetermined frequency, means to impress the oscillations on said signal initiating means, and means to transmit the control signals, a second circuit 40 including oscillation generating means excited periodically by the transmitted signals to generate oscillations of a frequency bearing a predetermined ratio to the frequency of the control signals, and a device controlled by the oscillations 45 generated by the last mentioned means.

5. A system of the character described comprising, in combination, a normally unexcited oscillation generating circuit, means to initiate periodically control signals to excite the said circuit thereby producing oscillations of a definite frequency and a device controlled by said oscillations, an additional normally unexcited oscillation generating circuit controlled by said control signals to produce oscillations the frequency 55 of which is equal to that of the first mentioned oscillations and a second device controlled by the second mentioned oscillations produced so that the said devices are operated in a predetermined timed relationship.

6. A system of the character described comprising, in combination, means to initiate periodically control signals, a normally unexcited oscillation generating circuit controlled by the signals to produce oscillations of a predetermined 70 frequency, means to impress the said oscillations upon the first mentioned means to sustain the initiation of the control signals, a device controlled by said oscillations, an additional normally unexcited oscillation generating circuit 75

controlled by the said control signals to produce oscillations the frequency of which is equal to that of the first mentioned oscillations, and a second device controlled by the second mentioned oscillations produced so that the said devices are operated in a predetermined timed relationship.

7. A system of the character described comprising, in combination, a normally unexcited oscillation generator, means to control the operation of the generator to produce oscillations of a predetermined frequency, a device controlled by said oscillations, and means to initiate periodically control signals, a second normally unexcited oscillation generator controlled by said signals to produce oscillations of a frequency bearing a predetermined relationship to that of the first mentioned oscillations, and a device controlled by the second mentioned oscillations so that the said devices are operated in a predetermined timed relationship.

8. A system of the character described comprising, in combination, means to generate oscillations of a predetermined frequency including means to initiate periodically control signals, a device controlled by said oscillations generated, a normally unexcited oscillation generating means, means controlled by the said signals to impress discrete excitation impulses on said oscillation generating means to produce oscillations the frequency of which bears a predetermined relationship to that of the first mentioned oscillations, and a device controlled by the last mentioned oscillations so that the said devices are operated in a predetermined timed relationship.

9. A system of the character described comprising, in combination, means comprising electron discharge means to generate oscillations of a predetermined frequency including means to initiate periodically control signals, a device controlled by said oscillations generated, a normally unexcited oscillation generating means, means comprising electron discharge means controlled by said signals to impress discrete excitation impulses on said oscillation generating means to produce oscillations, the frequency of which

bears a predetermined relationship to that of the first mentioned oscillations, and a device controlled by the last mentioned oscillations so that the said devices are operated in a predetermined relationship.

10. The method of generating supply energy for control purposes which comprises generating oscillations of a predetermined frequency for control purposes and periodic control impulses at one station, utilizing the control impulses to sustain further generation of the oscillations and to initiate control signals then transmitting the control signals to another station and utilizing the signals thereto to generate oscillations of the same said predetermined frequency so that the oscillations generated thereby for control purposes are in predetermined relationship with the oscillations at the first station.

11. A system of operating devices in timed relation comprising normally unexcited oscillation generators at remotely situated stations and the oscillation generator at one station being adapted to generate oscillations of a predetermined frequency for control purposes characterized by the fact that electron discharge means are provided for transmitting a series of discrete control signals and in timed relation with the generated oscillations to control the excitation of the oscillation generator at another station so that the oscillations generated thereby for control purposes are in predetermined timed relationship with the oscillations generated at the first station.

12. The invention set forth in claim 11 further characterized by the fact that control means are provided whereby one time signal is transmitted for each complete oscillation generated at the first mentioned station.

13. The invention set forth in claim 11 further characterized by the fact that means are provided whereby the timed relation of the said control signals and oscillations generated at the first mentioned station can be altered.

CLYDE J. FITCH.
